UNITED STATES PATENT OFFICE.

EDWARD RHODES, OF DRESDEN, OHIO, ASSIGNOR OF ONE-HALF TO JOHN W. P. REID, OF DRESDEN, OHIO.

CORE FOR BUILDING-BLOCKS.

No. 879,066.

Specification of Letters Patent.

Patented Feb. 11, 1908.

Application filed July 25, 1906. Serial No. 327,646.

To all whom it may concern:

Be it known that EDWARD RHODES, a citizen of United States, residing at Dresden, in the county of Muskingum and State of Ohio, has invented certain new and useful Improvements in Cores for Building-Blocks, of which the following is a specification.

The invention relates to an improvement in building blocks and core therefor, and particularly to that class known as concrete blocks usually formed in molds.

The main object of the invention is the production of a block comprising means integral with the block for supporting and reinforcing the binding agent used in connection with the block, said means being so constructed as to eliminate all possibility of the binding agent becoming dislodged from its normal position and falling between the blocks.

Another object is to produce a block which shall possess the advantage above mentioned and at the same time allow perfectly free circulation of air in all directions in the interior of the block, thus insuring a practically dry wall, a condition conducing greatly to the strength and life of a structure and therefore much desired.

Another object of the invention is the production of a block which shall be as efficient and convenient in forming corners and "angles" as it is in straight wall construction and which shall require a less amount of mortar or other binding agent than is usually required by blocks of this class.

The invention will first be described in the following specification, taken in connection with the accompanying drawings, and then pointed out in the claims.

In the drawings, Figure 1 is a perspective of my improved block. Fig. 2 is a central, longitudinal section of a tier of blocks constructed according to my invention in position as units of part of a wall. Fig. 3 is a perspective of the core used in molding the interior of the block. Fig. 4 is a central, longitudinal section of the same, and Fig. 5 is a top plan of the same.

Referring now to the drawings, in which like reference numerals refer to like parts throughout the several views, 1 denotes a block constructed according to my invention and comprising an approximately rectilinear hollow structure with front wall 2, rear wall 3 and end walls 4 and 5 respectively. The

exterior faces 6 of both end walls are formed slightly concave, as shown in Fig. 1, for a purpose hereinafter set forth. Formed integral with the block and joining the front and rear walls thereof is a V-shaped bridge 7, 60 extending about one-half the depth of the block with its apex toward the bottom face of the same and having its upper face lying in a plane coincident with the plane of the upper face of the block, as shown in Figs. 1 65 and 2.

8 represents the core used in forming the interior of the block and comprises a hollow structure approximately oval in cross section and of such dimensions as to produce a block 70 of desired size.

9 denotes a bridge-forming notch cut from the upper face 10 toward the lower face 11 of the core a sufficient distance and of such configuration as to provide for forming the bridge 75 of predetermined shape and dimensions, in molding the block.

12 denotes inwardly-projecting lugs formed integral with the sides of the core near the upper face thereof and are adapted to be engaged by a removing tool in separating the core and block after the latter has been molded.

In forming the block, sufficient of plastic material desired is put into a mold, the face 85 of which may be, if required, of such design as to imitate rock, chiseled stone, etc., the core inserted with its notch 9 uppermost in the center of the mold, the remaining quantity of material necessary put into the mold 90 and thoroughly tamped around the core which, when the material is sufficiently "set", is removed by means of a removing tool through the agency of lugs 12, when the core may, of course, be used in forming another 95 block.

In using the blocks as units in structures, a ground row is laid in ordinary manner with the binding agent placed on walls 2, 3, 4 and 5, as usual, and also in the space formed between the end walls of the blocks by the concave faces 6 of said ends. The row of blocks next above is arranged in the same relative longitudinal position as the row below it but is so spaced as to bring the mortar placed between the faces 6 of any two contiguous blocks in the upper row directly above the bridge 7 of the block immediately below them, as shown in Fig. 2, when, as will be obvious, all tendency of the mortar between 105 110

the faces 6 to fall into the block below will be overcome, it being effectively supported and securely held in normal position by the bridge 7 of the block below it, while at the same time less mortar will be required between said faces than ordinarily due to their concave formation which will also overcome any possibility of the mortar being forced from between the blocks in a transverse direction.

10. The blocks being approximately twice as long as wide, it will be apparent that in forming corners of structures the bridge 7 will be in position to perform the same function it accomplishes in straight wall construction but of course in corner work it will support throughout its length that portion of the binding agent lying contiguous the longitudinal face of the block.

It will be noted that the core is of oval form and of hollow construction and that the bridge-forming members or walls, by virtue of their relative dispositions, act as a most effective brace for the wall of the core and prevent its collapse or distortion under continued reuse.

It will be apparent from the above that I have provided a strong, easily molded block and simple core, the block possessing the desired advantages of supporting and holding in place the mortar used in connection therewith and of allowing unimpeded circulation of air in all directions and which requires but a small amount of binding agent in either plane construction or "angle" work.

35. While I have shown and described the core 8 as hollow, it is to be understood that, if desired, it can be provided with an upper wall to enable ready manipulation of the plastic material in filling the mold.

40. Having thus described the invention, what is claimed as new is:

1. A core for forming the opening in build-

ing blocks, comprising a hollow metallic body having each side wall formed with a V-shaped depression, and walls connecting the transversely-aligned edges of both said depressions, said depressions opening through one edge of the body walls and being of less depth than the depth of the body.

2. A core for forming the opening in building blocks, comprising a hollow metallic body having each side wall formed with a V-shaped depression, and walls connecting the transversely-aligned edges of both of said depressions, said depressions opening through one edge of the body walls and being of less depth than the depth of the body, and removing lugs projecting inwardly from the body walls in alignment with the depressions.

3. A core for building blocks comprising a metallic wall arranged in rounded configuration, and a V-shaped section bridging the space inclosed by the wall.

4. A core for building blocks comprising a hollow body of oval configuration, and a V-shaped section bridging the opening in said body, said section opening through the wall of the body to form V-shaped recesses therein.

5. A core for building blocks comprising a hollow body of oval configuration, a V-shaped section bridging the space included within the body and comprising relatively inclined walls terminating at their spaced edges in alignment with one edge of the body wall, said wall being cut away to form recesses to register with the space included between the inclined walls.

In testimony whereof I affix my signature in presence of two witnesses.

EDWARD RHODES
